UNITED STATES PATENT OFFICE.

FREDERICK W. MARTIN, OF MANHATTAN BEACH, NEW YORK, ASSIGNOR TO FRANK-LIN RAILWAY SUPPLY COMPANY, A CORPORATION OF DELAWARE.

OPERATING APPARATUS FOR FIRE DOORS.

Application filed April 19, 1920. Serial No. 375,042.

To all whom it may concern:

Be it known that I, FREDERICK W. MARTIN, a citizen of the United States, residing at Manhattan Beach, in the county of Kings and State of New York, have invented certain new and useful Improvements in Operating Apparatus for Fire Doors, of which the following is a specification.

This invention has reference to the provision of an improved form of actuating means for operating fire box doors particularly such as are used in conjunction with fluid pressure means either of air or steam as commonly employed on locomotive fire boxes.

The first of the objects of this invention is the provision of an operating apparatus of the character specified which will be economical to construct, which will be efficient and economical in operation, which can be readily and cheaply repaired and adjusted and which will secure effective and prompt actuation of the moving parts of the door with a minimum expenditure of power.

A further object of this invention is the provision of means in association with the apparatus specified which will produce a movement of the door parts with a minimum of shock or recoil and which will not interfere with hand actuation of the moving parts of the door when required.

A further object of the invention is the provision of operating mechanism of the character referred to which may be set in most convenient position for the foot of the fireman and at the same time not interfere with other adjacent operating parts mounted on a locomotive or with the clearance and freedom of the surface of the deck plate or floor of the locomotive cab.

The above, as well as such other objects as may hereinafter appear, I obtain by means of a construction which I have illustrated in preferred form in the accompanying drawings, wherein—

Figure 1 is a front elevation of a door apparatus having my improvements applied thereto; Figure 2 is an end view of a door apparatus with the actuating mechanism partially in section; Figure 3 is a view partially in section taken on the line 3—3 of Figure 2, and Figure 4 is an opposite end elevation showing the parts connected with

the door plates on the end opposite to the end to which the actuating piston and link is applied.

Referring now more particularly to Figures 1 and 4, it will be seen that I have therein indicated a door frame 1 having an upper swinging door plate 2 and a lower door plate 3.

The upper door plate 2 as well as the lower door plate 3 are pivotally mounted on either side by means of the pins 4 and are connected respectively by the links 5 and 6 with the rocker lever 7 that swings on a pivotal support attached to the frame 1.

The frame 1 is secured by suitable bolts 1^b upon the outside of the boiler head 1^c just over the aperture into the fire box marked 1^a in Figure 4.

As a means for readily holding the door in various opened positions, I provide a pivotally mounted latch 9 adapted to engage either the aperture 10 or 11 or the lower end of the upper door plate 2 as required and both the door plates 2 and 3 I prefer to make of double wall construction with an air space between, the admission to such air space from outside the door being through the apertures 12 and from the inside of the door through the apertures 13 in the inner wall 14.

As a convenient means for actuating the door by hand I provide a handle 15 and at one end of the upper door plate 2, I mount a lug 16 which carries a threaded pin 17 that engages a link 18 which forms a connection to another threaded pin 19 that is secured within the piston 20.

The piston 20 reciprocates in the cylinder 21 to which the air is admitted through the pipe that is attached by the threaded opening 22 subject to the control of the valve 23 carried in a chamber in the arm 24, there being a pivotal connection 25 at the outer end of the arm 24 which supports the cross lever 26 that is actuated by the foot treadle 27.

The cylinder 21 is mounted from the door frame 1 by means of suitable securing devices such as the bolts 28 shown in Figure 1 and the piston 20 is connected to the link 18 by a pin 19 which extends out through a slot in the side of the cylinder.

I prefer to use a piston without packing rings, but of differential diameters and so

connected by the ports and passages that when the operating valve 23 is raised from its seat, the pressure from the inlet opening 22 will pass into the chamber under the 5 large end of the piston and force it upward transmitting the movement through the link 18 to the upper door plate 2 from which the power will be transmitted in turn by means of the links 5 and 6 at the opposite 10 end of the door and the rocker lever 7 to the lower door plate 3 so that the two door plates will move in unison.

When the piston 20 travels upward to nearly the end of its stroke it comes in contact with the air valve 29 which is held down by a spring 30, raising it from its seat and admitting air on top of the piston, the supply coming through the inlet pipe connection 31.

20 As the upper end of the piston is of slightly smaller diameter than the lower end, this air pressure thus admitted on the top of the piston does not prevent the latter travelling its full stroke, but it does serve 25 to nearly balance the pressure upon the large end and thus prevents the doors from slamming open with violence.

As an additional means for securing quiet action, I arrange the link 18 so that when 30 the door is wide open such link connection will be almost in a direct line with the connection where it joins the piston and with the door pivot pin as shown in dotted lines in Fig. 2, by which arrangement as the door travels upward, the power for opening the 35 doors gradually decreases.

This arrangement of the link 18 aids materially in preventing the doors from slamming open with any degree of force.

40 When the pressure is removed from the treadle 27, the valve 23 closes cutting off the supply of air to the underside of the piston 20 and allowing the air to escape from below the piston so that the pressure which 45 still remains upon the upper end of the piston, (the valve 29 at the extreme travel of the piston being still open until the piston travels a slight distance downward,) will thus serve to start the door toward the closed 50 position. After the upper door plate, however, has swung out so that its weight will cause the door to close by gravity, the upper door plate being preferably somewhat larger and heavier than the lower one, the valve 55 29 descends cutting off the supply of air to the upper end of the piston and allowing the gravity of the upper door plate to complete the closing operation. The small 60 quantity of pressure admitted in the upper chamber in closing will not bind the piston as it leaks past the piston and out the slot in which the pin 19 works. Any other well known leakage expedient may be employed.

In order to prevent the doors from slaming 65 when they reach closed position, I

provide a double exhaust passage, the main exhaust taking place through the passages 31 and 32 shown in Figure 3 which is cut off, however, by the piston when it approaches the end of its downward stroke as 70 indicated by the dotted line at 33 leaving only a small restricted exhaust port 34 through which the air in the end of the cylinder below the piston may escape to the outlet passage 35.

75 The foot treadle 27 is carried on the end of an adjustable horizontal bar 36 which is provided on its upper surface with a series of notches 37 arranged to engage with a latch 38 held down by the weight 39.

To provide a swing or rotative movement of the treadle 27 and bar 36 the depending bracket in which they are carried is pivotally mounted upon a serrated washer 41 carried by a bolt 42 that has threaded engagement with the lever 26 and in rotation may be locked in adjusted position by means of a lock bolt 43. By the arrangement described the vertical adjustment of the foot treadle 27 may be varied to suit the operator's requirements by merely screwing the bolt 42 up or down in the lever 26.

80 While I have shown my operating apparatus as applied to a door of novel type invented by E. J. Bring and forming the subject matter of a copending application Serial No. 374,657, filed April 17, 1920, it is evident that some at least of the advantages of my improved apparatus may be obtained 85 if it be applied to other types of fire box doors.

90 I claim:

1. An operating mechanism for fire box doors comprising in combination a fluid actuated piston, connections from said piston to the door to be operated, said connections being attached to the piston and the door in position to produce a gradually decreasing application of force in the opening of the door and to aid in cushioning the door at 100 the end of its opening movement.

105 2. An operating mechanism for fire box doors comprising in combination with the door a differential piston, means for admitting fluid pressure to the larger end of said piston to open the door and means for admitting fluid pressure to the smaller end of said piston to cushion the opening movement of the door when near the end of its travel, said last mentioned means being constructed 115 to utilize the cushioning air to start the door in its closing movement and the door being gravity operated to closed position.

120 3. An operating mechanism for doors having a pair of pivotally mounted door plates, a fluid actuated piston for moving said plates, a connection whereby the force of the piston is transmitted to the plate, said connection being attached to the piston and the door in position which will cause the 125

connection to come nearly into line with the pivotal support of the door plate when the door is in opened position.

4. Operating mechanism for actuating fire box doors comprising in combination fluid pressure actuating means, valvular means for controlling the admission and exhaust of air to and from said actuating means, lever mechanism for actuating said valvular means and an actuating treadle for said lever mechanism having a vertical pivot on the lever mechanism to permit of radial adjustment of the pedal with relation thereto.

5. Operating mechanism for actuating fire box doors comprising in combination fluid pressure actuating means, valvular means for controlling the admission and exhaust of air to and from said actuating means, lever mechanism for actuating said valvular means and an actuating treadle for said lever mechanism having a vertical pivot on the lever mechanism to permit of radial adjustment of the pedal with relation thereto, and means for securing longitudinal adjustment 25 of said treadle in relation to its pivotal support.

6. In combination, a fire door frame, a pair of door sections pivoted thereon to swing on a substantially horizontal axis 30 transversely of the door opening, a substantially vertically arranged fluid pressure actuating means, and a connection between the upper section and said actuating means.

7. In combination, a fire door frame, a

pair of door sections pivoted thereon to 35 swing on a substantially horizontal axis transversely of the door opening, a substantially vertically arranged fluid pressure actuating means, and a connection between the upper section and said actuating means, said 40 upper section being also connected with the lower.

8. In combination, a fire door frame, a pair of door sections pivoted thereon to swing on a substantially horizontal axis 45 transversely of the door opening, a substantially vertically arranged fluid pressure actuating means, and a connection between the upper section and said actuating means, said 50 upper section being also connected with the lower and being heavier.

9. In combination, a fire door frame, a pair of door sections pivoted thereon to swing on a substantially horizontal axis, a differential piston, means for admitting fluid 55 pressure to the larger end of the piston to open the door sections, and means for admitting pressure to the smaller end to cushion the opening movement of the door when near the end of its travel and start 60 the sections in closing movement, the upper door section being heavier and being operatively connected to the piston and the lower section.

In testimony whereof, I have hereunto 65 signed my name.

FREDERICK W. MARTIN.
